CLAIM

The ornamental design for a light emitting diode lamp, as shown and described.

DESCRIPTION

FIG. 1 is a perspective view of the light emitting diode lamp showing our new design;

FIG. 2 is a front view thereof;

FIG. 3 is a back view thereof;

FIG. 4 is a right side view thereof;

FIG. 5 is a left side view thereof;

FIG. 6 is a plan view thereof;

FIG. 7 is a bottom view thereof; and,

FIG. 8 is an enlarged cross-sectional view taken along line 8-8 of FIG. 2.
